UNITED STATES PATENT OFFICE.

HOWARD J. FERRIS, OF HARVARD, ILLINOIS, ASSIGNOR TO HUNT, HELM, FERRIS & COMPANY, OF HARVARD, ILLINOIS, A CORPORATION OF ILLINOIS.

QUICK-DEMOUNTABLE TOY CONSTRUCTION.

Application filed July 9, 1925. Serial No. 42,601.

This invention relates to quick demountable toy constructions and is fully described in the following specification and shown in the accompanying drawings, in which:

5 Fig. 1 is a front elevation, partially in section, of a front wheel of a pedal car embodying the invention;

Fig. 2 is a vertical section on the line 2 of Fig. 1;

10 Fig. 3 is a horizontal section on the line 3 of Fig. 1;

Fig. 4 is an enlarged vertical section through the front wheel;

Fig. 5 is a section on the line 5 of Fig. 4;

15 Fig. 6 is a partial section similar to Fig. 4, but showing a modified form of the circular construction;

Fig. 7 is a side elevation of the axle;

Fig. 8 is a section on the line 8 of Fig. 6;

20 and Fig. 9 is a detailed view of the inner end of the pedal crank as viewed from line 9 of Fig. 6.

The embodiment illustrated in Fig. 1 comprises a front wheel 10, journaled as will later be described, between front fork members 11 which are secured to a tube 12 by means of a bolt 13. This tube is journaled in a bearing consisting of a sleeve 14 and upper and lower dished plates 15 and 16, the whole being secured to the platform 17 by means of bolts 18.

35 The tube 12 preferably terminates flush with the top of the sleeve 14 and is readily insertable in and removable from this sleeve. A steering shaft 19 is insertable into the hollow tube 12 and has a slot 20 in the lower end which passes over the bolt 13 so that as the boy operating the device grasps the 40 handles 21 he may turn the shaft 19 and through this the front forks 11 and front wheel 10 to steer the pedal car shown.

A spring 22 (Fig. 2) is secured to the lower end of the tube 12 by means of a rivet 45 23 and carries a plunger 24 which passes through an opening in the side of the tube 12 and is adapted to engage a recess or depression 25 in the shaft 19. The washer 26 is placed above the flanged sleeve 14 and a snap ring 27 is placed a little above the washer in a groove 28 in the shaft 19.

To assemble the device as shown the tube 12 is inserted from below into the sleeve 14

and the shaft 19, and is inserted from above and pressed down until the plunger 24 snaps 55 into the recess 25.

To remove the steering shaft and front fork the operator pulls up on the steering shaft 19 until the recess 25 is withdrawn from beneath the plunger 24 when the shaft 60 and front fork can be removed from the sleeve 14. Thus a quick and easy method is provided for assembling and disassembling this unit of a toy vehicle such as the pedal car here illustrated. This is of considerable importance in vehicles of this type 65 to ship the parts disassembled and to quickly and easily assemble them before using.

In Fig. 4 is shown a somewhat similar method for disassembling the front wheel 70 10 from its pedal cranks and from the steering fork 11. This wheel consists of two oppositely dished disks 29 which are mounted upon a hollow shaft 30 preferably of polygonal cross-section. A spacer 31 is secured 75 to one side of this shaft by means of a rivet 32 and serves as a spacer for the disks 29. Cranks 33 of a square or other polygonal cross-section are fitted into the hollow shaft 30 and have recesses 34 therein which are 80 adapted to engage plungers 35 which are carried by springs 36, the springs being fitted to the shaft 30 by means of a rivet 37.

The crank 33 is given a fairly close fit 85 in the inner race member 38 of a ball bearing 39 which is carried in a housing 40, the latter being secured to the lower end of the fork 11.

To disassemble the construction shown in Fig. 4, the cranks 33 are removed by a strong 90 pull on each which withdraws it from the shaft 30, thereby permitting the wheel 10 to be withdrawn from the fork 11. In reassembling, the wheel 10 is placed in the position shown in Fig. 4 and the cranks 33 95 inserted from the side so that the recesses 34 are engaged by the plungers 35 which will retain the cranks in place until sufficient force is again used to withdraw them. Owing to the squared section of the cranks 33 and the squared hole into which these fit, the cranks will cause the shaft 30 to turn with them and this in turn, owing to its squared cross-section fitting into the flattened hole in the disks 29 will drive the front 100 wheel 10. 105

In Fig. 6 is shown a modified form of this device in which the shaft 30^a is provided with turned journals 30^b which fit into suitable bearings in the ends of the front forks 11^a. Notches 30^c are formed in the turned ends 30^b which are adapted to receive ears 33^b on the round cranks 33^a. The cranks 33^a are yieldingly held by the same means as that which is shown in Fig. 4 and which has previously been described. The outer surface of the shaft 30^a is made hexagonal, and a positioning plate 31^a secured thereon by means of a rivet 32^a.

While I have shown and described but a few embodiments of this invention, it is to be understood that it is capable of many modifications. Changes therefore in the construction and arrangement may be made which do not depart from the spirit and scope of the invention as disclosed in the appended claims.

I claim:

1. In a quick-demountable toy construction, a hollow member, a driving member insertible therein, coacting means for preventing relative rotation of said members, and yieldable means for holding said driving member in said hollow member but permitting its withdrawal when a pull of more than a predetermined amount is exerted.
2. In a quick-demountable toy construction, a hollow member, a driving member insertible therein, coacting means for preventing relative rotation of said members, and a spring-pressed plunger carried by one of said members and engageable in a depression in the other for holding said driving member in said hollow member but permitting its

withdrawal when a pull of more than a predetermined amount is exerted.

3. In a quick-demountable toy construction, a hollow member, a driving member insertible therein, coacting means for preventing relative rotation of said members, a spring-pressed plunger carried by one of said members and engageable in a depression in the other for holding said driving member in said hollow member but permitting its withdrawal when a pull of more than a predetermined amount is exerted, and means limiting the inward movement of the driving member into the hollow member.

4. In a toy vehicle, a shaft, bearings therefor, a wheel, said shaft having longitudinal splines fitting into corresponding openings in said wheel for securing said wheel on said shaft.

5. In a toy vehicle, a shaft having longitudinal splines, and a double disk wheel, said disks having openings fitting said splines and means for positioning said wheel longitudinally of said shaft.

6. In a toy vehicle, a shaft having longitudinal splines, a double disk wheel, said disks having openings fitting said splines and means for positioning said wheel longitudinally of said shaft, and bearings at the ends of said shaft.

7. In a toy vehicle, a shaft having longitudinal splines, a double disk wheel, said disks having openings fitting said splines and means for positioning said wheel longitudinally of said shaft, the ends of said shaft being turned to form journals, and bearings thereon.

HOWARD J. FERRIS
